CIGAR MACHINE TRIMMING AND
KNURLING MECHANISM

Carl Olsson, Brooklyn, N. Y., assignor to International Cigar Machinery Company, a corporation of New Jersey

Application May 29, 1941, Serial No. 395,798

19 Claims.

(Cl. 131—29)

This invention relates to cigar machines, and more particularly to mechanism for removing trimmed cigar ends and chips of tobacco from either the knurler or trimming knives or both in order to prevent deposits of tobacco waste, which might cause possible damage to cigars being handled, from building up thereon.

In the formation of certain types of cigars in which both ends are trimmed, it is found advisable to knurl the head ends thereof in order to seal the wrapper and binder relative to the filler, and restore the shape of the head end, if distorted by the trimmers. However, because of the trimming operations on the ends of each cigar processed, small trimmed off end portions will be formed, and chips and small particles of tobacco may be present at the trimming zones. Since the trimmed off ends usually have some paste, and tobacco contains sticky substances, such as gum, there is a tendency for the trimmed off portions and waste tobacco to stick and cling to the knurler and trimmers or be transferred from the head end trimmer to the knurler and build up thereon. As a result of accumulations of tobacco on the knurler, its cigar end smoothing surfaces become bumpy and uneven and may thereby cause tearing of the wrappers and/or binders adjacent the trimmed head ends, or even cause the ends to be broken down or distorted. Accordingly it is the main object of my invention to provide means for trimming the ends of cigars and removing cut off tobacco end portions and chips of tobacco tending to adhere to and accumulate on either the knurler or trimmers or both.

It is a further object of my invention to provide means for directing a cleaning fluid upon the surfaces of one or more of the members which complete the fabrication of the ends of cigars in order to insure against damage to the cigars being handled.

My invention also consists in the provision of means for providing a blast of air of short duration for several purposes such as blowing the flag end of a wrapper from a wrapper carrier of a cigar machine, and expelling from cigar end manipulating devices small particles of tobacco and cigar end trimmings tending to cling thereto, and which, if allowed to accumulate thereon, would cause damage to cigars treated thereby.

It is a further object of my invention to provide a source of fluid under pressure, such as compressed air, for blowing the flag end of wrappers from a wrapper carrier, and use a part of this fluid in conjunction with timed coating mecha-

nism for cleaning the knurling device which operates upon the head ends of cigars.

The invention also consists in the provision of mechanism for trimming and knurling cigar ends and for cleaning these mechanisms by the use of compressed air after each has performed its designed functions.

An added object of my invention is to provide a flag pump blow-off mechanism, conduct compressed air therefrom and direct it upon the cigar end finishing knurler for removing therefrom particles and waste portions of tobacco tending to cling thereto.

My invention also consists in the provision of mechanism for controlling the operation of the trimming knives and knurler so that at substantially the same instant an air blast issues from the flag blow-off nozzle to expel the flag end of a wrapper from the wrapper carrier, the trimming knives and knurler are located in their inoperative positions and a cleaning air blast is directed upon either or both to effect the removal of small particles or pieces of tobacco tending to cling to and build up upon the knives and knurler.

With these and other objects not specifically mentioned in view, the invention consists in certain combinations and constructions which will be hereinafter fully described, and then set forth in the claims hereunto appended.

In the accompanying drawings which form a part of this specification and wherein the several reference characters designate the same or like elements:

Figure 1 is a partial sectional elevation showing the subject of this invention installed in the re-rolling unit of a cigar machine;

Figure 2 is a detached detail, to a larger scale, at the nozzle end of the device;

Figure 3 is a sectional view taken on line 3—3 of Figure 2;

Figure 4 is an end view of the knife operating mechanism;

Figure 5 is a side view partly in section of a detail of the trimmer operating mechanism; and

Figure 6 is a plan view of the same detail on line 6—6.

Referring to the drawings which show a preferred form of my invention, a cigar C is shown held by gripper fingers 15 and 16 after having been transferred from the wrapping mechanism, designated generally at W by a suitable transfer device T to rerolling drum 12 in a manner similar to that described in co-pending patent application, Serial No. 183,405, filed January 5, 1938, by

H. H. Wheeler, now Patent No. 2,316,828, issued April 20, 1943.

The construction and operation of the rerolling mechanism may be similar to that described in co-pending patent application, Serial No. 189,300, filed February 8, 1938, by H. H. Wheeler, in which the rerolling drum 12 is described. Shaft 28 carries a gear 29 which meshes with and is oscillated by a gear segment 30 on arm 31. Since this mechanism forms no part of the present invention further description is deemed unnecessary.

As the cigar C leaves the drum 12 and is gripped by fingers 15 and 16 it passes between two pairs of trimming knives 17, 18 and 122, 123, which, at this time, are spread apart to allow the untrimmed cigar C to clear (Figure 1).

The knurler 14, which also functions as a cigar locator, now advances and contacts the head end of the cigar C and pushes it axially to locate it in a predetermined position where it is acted upon by the trimming knives 17, 18 and 122, 123 which are then moved to trimming location as shown in dotted lines in Figures 1 and 2. Each cigar is gripped lightly in grippers 15, 16 during the cigar locating operation, and then held firmly therein during the trimming and final knurling.

The trimmers are normally held some distance away from the ends of rolling drum 12, but after the cigar to be treated has been located, are moved into trimming position and then close upon the ends of the cigar projecting through the knives to trim them as desired. Since the operating means for the knives are both the same but one will be described. Knives 122, 123 are mounted on a flanged sleeve 95 loose on shaft 96 supported on bearing block 37 and in a bearing 97 of housing 11. On sleeve 95 are also mounted a flanged collar 98 carrying a coil spring 99 and a collar 100, the members 122, 123, 95 and 98 being clamped together by nuts 101 screwed against a spring washer 102 on sleeve 95. The collar 100 in the bottom of its periphery has a radial hole into which loosely fits a pin 103 carried at the end of an arm 104 pivoted on a stud 125 adjustable in the slot 106a of a bar 106 fastened to block 37 and housing 11. Arm 104 has a follower 107 engaging with an adjustably mounted drum cam 124 on shaft 24, which shaft has one end mounted in a bearing abutment on housing 11 and its other end suitably supported and driven by mechanism (not shown) similar to that disclosed in co-pending Wheeler application, Serial No. 189,300. Cam 124 is provided with a set screw 124a adapted to coact with slot 124b to secure the cam in adjusted position. When portion 126 of cam 124 engages follower 107, arm 104 moves the trimmers from full to dotted line or cutting position. The location of knives 122, 123 or 17, 18 can be varied for any cigar merely by adjusting the position of cams 124 or adjusting the fulcrum of levers 104 in bars 106. If much adjusting is necessary, both of the above mentioned adjustments must be made. An elongated cam 111 engages with projections having cam followers 109 and 110 on the knives for opening and closing them upon cigar ends at the proper time by means of a crank arm 113 fixed to an end of cam 111 connected to link 114 connected to a lever 115 mounted on pivot 116 in an abutment 117 and provided with a cam follower 118 operating in a cam track 119 of a cam 26, all in a manner similar to that shown in the above referred to Wheeler application, Serial No. 189,300.

The cigar locator and knurler 14 is carried by 75

a horizontal shaft 23 slideable in bearings in housing 11 and cover 21. Shaft 23 is driven by a bevel gear 60 meshing with bevel gear 43 on shaft 23 and held against axial displacement by a collar 54 bearing against an internal shoulder in bracket 22, the hub of gear 43 having a long keyway 56 and a key 57 connecting it to and permitting axial movement of shaft 23, after the same general arrangement as shown in co-pending Wheeler application, Serial No. 189,300, above referred to. The lever 150 carries a roller 46 which engages collar 45 on shaft 23. Lever 150 is pivoted at 151 and its lower arm 152 is connected by link 153 to a cam lever 154 fulcrumed at 155 and has a roller 156 in engagement with a cam 157 on shaft 158.

The roller 156 rests on the high portion of cam 157 while the cigar C is being rerolled by drum 12. As the cigar is delivered to the grippers 15 and 16, the roller 156 enters the depression 159 of the cam thereby permitting the spring 50 to advance the knurler 14 to a predetermined position governed by the depth of the depression 159.

The trimming knives 17, 18 and 122, 123, in the meantime, have moved into the dotted line positions of Figures 1 and 2 and as the cam roller 156 rides out of depression 159, thus withdrawing the knurler 14, the knives 17, 18 and 122, 123 will close upon and trim the two projecting ends of the cigar C.

During this operation roller 156 has been riding on the high portion 160 of cam 157, but as the knives 17, 18 and 122, 123 open, the roller 156 descends to the low portion 161 of cam 157 thus permitting spring 50 to again advance the knurler 14 and perform the final knurling operation, the cigar at this time, being held firmly in the gripper fingers 15 and 16. Cam 157 is fixed to rotating shaft 158 driven in any suitable manner from the main shaft of the machine. A sprocket 183, also carried by shaft 158, through chain 184 and sprocket 185 mounted on shaft 181 rotates cam 178 for purposes described hereinbelow. An adjustable stop screw 185a coacts with an extension 152a of lever arm 152 in case it is desired to control the amount of forward advance of knurler 14 up to the full distance allowed by depressed portion 161 of cam 157.

As the follower 156 rides upon the high portion 162 of cam 157, the knurler is withdrawn and the knives 17, 18 and 122, 123 are moved into their full line positions clearing the way for the delivery of the next cigar from the rerolling drum 12 for locating, trimming and knurling after the gripper fingers 15 and 16 have released the cigar C for discharge therefrom.

As a result of the trimming operations and knurler movements, small trimmed off portions will be formed and chips or small pieces of tobacco may be present and tend to stick or cling to either the knurler 14 or trimmers 17, 18 and 122, 123, or both. This is due largely to the fact that tobacco contains sticky materials, such as gum, and also because of paste which is placed on a wrapper prior to its being applied to a bunch at the wrapping unit W. If this waste is allowed to adhere to or build up on the knurler and/or trimmers, it will cause damage to subsequent cigars treated thereby. For instance, particles of tobacco on the knife blades will prevent even cutting and tend to dull them. Also, with respect to the knurler 14, the presence of tobacco or waste clinging or adhering to the smoothing surface or knurling surfaces thereof will cause possible tearing or rupturing of the ends of cigars be-

ing knurled. Especially is this true in cases where both ends of cigars are cut off and the trimmed head end is knurled a second time, as in the structure illustrated in Figure 1. In addition to smoothing the wrapper upon a cigar end, the second knurling is also valuable in restoring roundness to trimmed ends of cigars if they become distorted in any manner during the trimming operations. Therefore, in order to obviate any danger of damage which might occur in trimming and knurling cigars, mechanism has been provided for effecting the positive removal of trimmed off ends and preventing accumulations of waste tobacco, fines, and the like from building up on the knurler and/or trimmers.

In the mechanism shown in Figure 1, an air compressor pump P supplies air to a reservoir R from which it is led by a pipe 163 mounted in a hollow standard 186 fixed to the machine frame to a valve 164. A nozzle 165 is fixed to the top of standard 186 for coaction with suction head 166 of the wrapper leaf transfer in order to release the flag end of a wrapper at the proper time when it is to be applied to a bunch in the wrapping mechanism W. This mechanism may be of the same general type as that shown in Wheeler Patent No. 2,215,490, granted September 24, 1940. However, since the specific nozzle 165 and suction head 166 form no part of this invention, further description and showing is deemed unnecessary.

To the top of nozzle 165 is connected in any desired manner a conduit such as a flexible hose 167 coupled to a second conduit 168 having a discharge opening adjacent knives 122, 123 and knurler 14 preferably in their retracted positions for waste removal after the operation of one or both as will appear hereinafter.

Attached to valve stem 170 is a lever 171 connected by a link 172 to cam lever 173 pivoted on shaft 174. A cam follower 175 carried by arm 176 of lever 173 is urged by spring 177 suitably fixed to the machine table and arm 173 to track cam 178. By means of this structure, whenever cam follower 175 descends to low portion 179 of cam 178, the valve stem will turn and admit a blast of air to nozzle 165 and hose and pipe line 167, 168 which direct the blast through nozzles 186, 182 upon the operating surfaces of knives 122, 123 and knurler 14 thereby effecting a positive removal of pieces and chips of tobacco which might otherwise adhere to either the knives or knurler or both.

If desired, either of the nozzles might be omitted in which case the fluid blast would be conducted only to the knurler 14 or trimming knives 122, 123. As shown in Figure 3, nozzles 180, 182 are connected to supply conduit 168 through a valve V so that by mere movement of handle 187, the fluid can be shut off from one or the other of the nozzles, or by setting cut-off plate 189 at neutral position (as shown in Figure 3) both nozzles may remain open and operative.

Located directly beneath the trimming mechanism is a chute 120 into which waste tobacco and pieces fall. A pneumatic conduit 121 attached thereto may be provided with suction for conveying the same to a waste receptacle.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a cigar machine, the combination with a support for a cigar, of means for trimming the ends of said cigar on said support, a knurler for knurling one of said trimmed ends, mechanism for moving said knurler from an inoperative position into engagement with said end of said cigar to knurl said trimmed end of said cigar and then return said knurler to inoperative position, and means operated in timed relation with said trimming means and said knurler for directing compressed air upon said trimming means adjacent said knurler when said knurler has been returned to said inoperative position for removing therefrom waste tobacco deposited thereon as a result of said trimming and knurling operations.
2. In a cigar machine, the combination with a pair of grippers for holding a cigar, and knives for trimming an end of a cigar held by said grippers, of a knurler movable into and out of engagement with an end of said cigar, and means operated after said knurler has been moved out of engagement with said cigar for blowing a blast of air upon said knurler to remove therefrom waste pieces of tobacco deposited thereon during the knurling operation.
3. In a cigar machine, a knurler, means for rotating said knurler, means for moving said knurler into and out of engagement with an end of a cigar, means for trimming said end of said cigar, and means located adjacent said trimming means and said knurler and operated in timed relation therewith when said knurler has been moved out of engagement with said end of said cigar for blowing compressed air on said trimming means and said knurler to remove therefrom any waste tobacco which may tend to cling thereto as the result of such operations.
4. In a cigar machine having a cigar wrapping station provided with means for applying a wrapper to a cigar bunch at said station, and a device for rerolling a cigar delivered from said station; a pair of grippers receiving said rerolled cigar, means for trimming the ends of said cigar, a knurler, means for moving said knurler from an inoperative position into and out of engagement with an end of said cigar prior to and after said trimming operation, and means mounted for coaction with said knurler at said inoperative position for removing waste tobacco tending to adhere to said knurler as the result of said knurling operations.
5. In a cigar machine having a cigar wrapping station provided with means for applying a wrapper to a cigar bunch, and a device for rerolling a cigar delivered from said station; a pair of grippers receiving and holding the rerolled cigar, means for trimming the ends of said cigar, a knurler, means for moving said knurler into engagement with an end of said cigar to locate it in said grippers, and means for operating said trimmer to trim the ends of said located cigar, means for again moving said knurler into engagement with a trimmed end of said cigar to knurl the same, and means operative after the operation of said knurler for directing a blast of compressed air upon said knurler for removing therefrom any waste tobacco tending to cling thereto as a result of said operations.
6. In a cigar machine having a cigar wrapping station provided with means for applying a wrapper to a cigar bunch at said station, and a device for rerolling a cigar delivered from said station; a pair of grippers receiving said rerolled cigar, means for trimming the ends of said cigar; a knurler, means for moving said knurler into and

out of engagement with an end of said cigar prior to and after said trimming operation, and means operative after the operation of said knurler for directing a blast of compressed air upon said knurler for removing waste tobacco and particles tending to adhere to said knurler as the result of said end treating operations.

7. In a cigar machine having a cigar wrapping station provided with means for applying a wrapper to a cigar bunch at said station, and a device for rerolling a cigar delivered from said station; a pair of grippers receiving said rerolled cigar, means for trimming the ends of said cigar, a knurler proximate said trimming means, means for moving said knurler into and out of engagement with an end of said cigar prior to and after said trimming operation, and means mounted for coaction with said knurler for directing a blast of compressed air upon said trimming means for removing therefrom cut off and waste particles of tobacco tending to adhere to said trimming means.

8. In a cigar machine having a cigar wrapping station provided with means for applying a wrapper to a cigar bunch at said station, a wrapper carrier for delivering a wrapper to said station, and means for blowing off the flag part of the wrapper from said carrier, a knurler, means for holding a cigar delivered from said station for operation thereupon by said knurler, means for moving said knurler into and out of operative engagement with said cigar held by said holding means, means operative after said knurler has first engaged and disengaged said cigar end for trimming said end, said knurler moving means being operative to again move said knurler into engagement with the trimmed end of a cigar, and means operating simultaneously with the removal of said flag part of said wrapper from said carrier for blowing a blast of air upon said knurler for cleaning the same.

9. In a cigar machine having a wrapping device provided with means for applying a wrapper to a bunch in said device, and a wrapper carrier for delivering a wrapper to said bunch in said device, a cigar trimming and knurling station, means for holding a cigar at said station, means for trimming a cigar end at said trimming and knurling station, and means operative substantially simultaneously for blowing a part of a wrapper from said carrier at said wrapping station for application about a bunch, and for directing a blast of compressed air upon said trimming means for removing therefrom particles of tobacco tending to cling thereto as the result of said trimming operation.

10. In a cigar machine, a cigar trimming and knurling station, means for holding a cigar at said station, a cigar end trimmer, a knurler, means for moving said knurler to locate said cigar for trimming, means for moving said trimmer into and out of engagement with said located cigar to trim an end thereof, means for moving said knurler into engagement with the trimmed end of said cigar to finish the end of said cigar, and means operative in timed relation with and after said trimmer and knurler have performed their functions on said cigar for blowing a blast of air on said knurler and trimmer for cleaning them of particles of tobacco tending to cling thereto.

11. In a cigar machine of the type having a cigar wrapping station provided with means for applying a wrapper to a cigar bunch at said station, a wrapper carrier for delivering a wrapper to a bunch at said station, and a rerolling mech-

anism to which wrapped bunches are delivered; end finishing members coating with said rerolling mechanism for finishing cigars, a source of supply of air, and means operative in timed relation with the movement of said carrier for directing air from said source to blow the flag end of a wrapper from said carrier, and to direct a cleaning stream upon said members to expel therefrom waste tobacco tending to cling thereon.

10 12. In a cigar machine, a cigar finishing station, a trimmer and a knurler located at said finishing station, means for imparting separate motions to said trimmer and knurler for trimming and knurling an end of each cigar delivered to said finishing station, and means operative in timed relation with said trimmer and knurler for directing a gaseous cleaning fluid upon said trimmer and knurler after each has performed its respective functions to remove from said trimmer and knurler pieces of tobacco tending to cling thereto.

15 13. In a cigar machine of the type having a wrapping station provided with means for wrapping bunches located therein, a wrapper carrier for delivering wrappers to said bunches at said station, a cigar finishing station, a trimmer and a knurler located at said finishing station, means for imparting separate motions to said trimmer and knurler for trimming and knurling an end of each cigar delivered from said wrapping station to said finishing station, means for directing a cleaning fluid upon said trimmer and knurler after each has performed its respective functions, said last named means comprising a 20 source of supply of fluid, a conduit connecting said source of supply with said wrapper carrier for directing fluid from said source of supply to said trimmer and said knurler, and means operative in timed relation with the movement of said carrier for controlling the passage of said fluid from said source through said conduit.

25 14. In a cigar machine of the type having a wrapping station provided with means for wrapping bunches located therein, a wrapper carrier for delivering wrappers to said bunches at said station, a cigar finishing station, a trimmer and a knurler located at said finishing station, means for imparting separate motions to said trimmer and knurler for trimming and knurling an end of each cigar delivered from said wrapping station to said finishing station, means for directing a cleaning fluid upon said trimmer and knurler after each has performed its respective functions, said last named means comprising a 30 source of supply of fluid, a conduit connecting said source of supply with said wrapper carrier for directing fluid from said source of supply to said trimmer and said knurler, and means operative in timed relation with the movement of said carrier for controlling the passage of said fluid from said source through said conduit.

35 15. In a cigar machine of the type having a wrapping station provided with means for wrapping bunches located therein, a wrapper carrier for delivering wrappers to said bunches at said station, a cigar finishing station, a trimmer and a knurler located at said finishing station, means for imparting separate motions to said trimmer and knurler for trimming and knurling an end of each cigar delivered from said wrapping station to said finishing station, means for directing a cleaning fluid upon said trimmer and knurler after each has performed its respective functions, said last named means comprising a 40 source of supply of fluid, ducts positioned for coaction with said carrier, trimmer and knurler, and a conduit connecting said ducts with said source of supply, and means operative in timed relation with the movement of said carrier for directing fluid from said source through said conduit and ducts.

45 16. In a cigar machine of the type having a wrapping station provided with means for wrapping bunches located therein, a wrapper carrier for delivering wrappers to said bunches at said station, a cigar finishing station, a trimmer and a knurler located at said finishing station, means for imparting separate motions to said trimmer and knurler for trimming and knurling an end of each cigar delivered from said wrapping station to said finishing station, means for directing a cleaning fluid upon said trimmer and knurler after each has performed its respective functions, said last named means comprising a 50 source of supply of air, a blow-off nozzle positioned for coaction with said carrier at said wrap-

ping station and ducts located adjacent said trimmer and knurler at said finishing station, conduits connecting said source of supply to said blow-off nozzle and ducts, and selective means for operating either or both of said ducts to blow fluid on said trimmers and/or said knurler.

16. In a cigar machine having a cigar finishing station, a knurler adjacent said station, devices for holding a cigar for finishing operations, means for moving said knurler from an inoperative position into and out of engagement with said cigars while held by said devices, and mechanism operative when said knurler has been returned to said inoperative position for directing a blast of air on said knurler to remove therefrom particles of tobacco tending to adhere to said knurler, said mechanism comprising a source of supply of air, a duct adjacent said knurler, and means for directing air from said source to said duct.

17. In a cigar machine having a finishing station, and means for holding cigars for finishing, spaced end trimmers for trimming the ends of said cigars, means for moving said trimmers into and out of an operative position for engagement with said cigar ends, means for operating said trimmers when said trimmers are located in operative position, and means positioned for coaction with one of said trimmers upon completion of said trimming operations and the return of said trimmer to inactive position for directing a blast of air on said trimmer to remove therefrom waste and particles of tobacco tending to adhere thereon.

18. In a cigar machine having a finishing station, means for holding a cigar for finishing operations on the end of said cigar, spaced end trimmers for trimming the end of said cigar while held, a knurler cooperating with one end of said cigar for locating said cigar for trimming and for knurling an end of said trimmed cigar, means for operating said trimmers to trim the ends of said cigar, mechanism for moving said knurler from an inoperative position into engagement with said end of said cigar, first to locate said cigar in said holding means and then to knurl said end of said located cigar and then return said knurler to inoperative position, and means operated in timed relation with said trimmers and said knurler when said knurler is in said inoperative position for directing a blast of air upon said trimmers and said knurler for removing from said trimmers and said knurler waste tobacco tending to cling thereto as a result of said trimming and knurling operations.

19. In a cigar machine the combination with means for holding a cigar, of a knurler, means for imparting to said knurler a plurality of cigar end engaging operations including a cigar locating operation for locating said cigar in said holding means, and a cigar knurling operation for knurling said located cigar, and means operative at the termination of said knurling operation for directing a blast of air upon said knurler to remove therefrom waste pieces of tobacco deposited thereon during the knurling operation.

CARL OLSSON.
